COSMETIC APPLICATOR

Jean L. Reedy, 7100 W. Touhy Ave., Niles, Ill.

Filed Dec. 9, 1959, Ser. No. 58,621

Term of patent 14 years

(Cl. D86—10)

Fig. 1 is an edge elevational view of a cosmetic applicator embodying my new design;

Fig. 2 is a side elevational view thereof, the side opposite thereto being substantially similar in appearance;

Fig. 3 is a side perspective view;

Fig. 4 is an end elevational view as seen from the blade end; and

Fig. 5 is an end elevational view thereof as seen from the handle end.

I claim:

The ornamental design for a cosmetic applicator, substantially as shown and described.
